CLAIM

The ornamental design for a bathtub tray, as shown and described.

DESCRIPTION

FIG. 1 is a front, right, top perspective view of the bathtub tray in the first state, showing my new design;

FIG. 2 is a rear, left, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a front, right, top perspective view of the bathtub tray in the second state.

The dashed broken lines in the figures are for the purposes of illustrating portions of the bathtub tray that form no part of the claimed design.

1 Claim, 9 Drawing Sheets
